BLADE GRADING MACHINE

John Stephen Burns, Walton-on-Thames,
EnglandApplication May 23, 1940, Serial No. 336,800
In Great Britain April 5, 1939

13 Claims. (Cl. 37—156)

This invention relates to blade grading machines, with more especial reference to road graders, patrols and maintainers used principally for making earth or gravel roads in which a blade is adjustably mounted on a steerable vehicle so as to be capable of cutting the earth and imparting the desired profile to the surface traversed or passed by the machine.

In my prior Patent No. 2,074,081 a construction of grading machine is described, including a longitudinally extending main frame mounted on wheels, a member transversely encircling the main frame and mounted thereon for rotation about a longitudinal and substantially horizontal axis, the said member carrying a plough frame with mouldboard and blade and means being provided for rotating it, for moving it up and down in an approximately vertical plane and for moving it laterally in regard to the main frame, thus to position the blade as regards depth of cut and sideshift.

In this prior construction the encircling member was formed as an annulus or ring embracing a control structure or subframe movable vertically and laterally in relation to the main frame through the medium of screwthreaded stems, and to enable final cambering adjustments in the position of the blade to be effected by actuation of the stems, independently in the same or opposite direction, resort was had to arcuate guides for slidably mounting the subframe or structure on the stems.

The present invention has reference to grading machines of this general character and has for its object to provide an improved construction enabling final adjustment and cambering of the blade to be effected if need be while the machine is at work, without the necessity for a sliding connection between the screwthreaded stems and the subframe.

Further and favorable objects will appear from the following description.

In accordance with the present invention the screwthreaded vertical stems are universally mounted at or near the extremities of the transverse guide members which are laterally adjustable in relation to the main frame, and the stems are anchored in relation to the subframe or control structure in turn carrying the annular member mounting the plough circle, the universal mountings for the stems riding a slide or guideway provided for the purpose on the subframe or control structure, thus to relieve the screwthreaded stems of bending moment.

In the case of patrols and maintainers, the

annular or ring member may be omitted and the plough frame or circle carried directly by the subframe structure since the range of blade movement, which may be of the order of 25° each way, afforded by the screwed stems is more than sufficient for these machines and indeed is adequate for all purposes other than steep sidesloping or battering.

In either event this subframe is preferably rectangular so that the plough frame or circle is conveniently mounted directly thereon for the patrol or maintainer or where the annular member is interposed to provide for the circular movement of the blade, this is readily and freely carried by rollers borne adjacent the corners of the rectangular subframe.

Advantageously, in addition to the normal unidirectional movement of the stems to modify the depth of cut, provision is made for actuating the stems independently or in opposite directions, thus finely to adjust the angle or camber of the blade and to this end the universal mountings for the screwthreaded stems at each end of the transverse members are trunnioned therein, one or both of the trunnions affording relative movement between the mounting and the transverse members to the degree necessary to accommodate the angular setting of the structure to the requisite extent, e. g., about 25° on each side of the horizontal.

The gearboxes for actuating the screwthreaded stems may be positioned at the extremities of the aforementioned transverse members, and may constitute the universal mounting in which case the screwthreaded stems are so anchored to the subframe or control structure as to be held against rotation or, alternatively, the stems themselves may be rotated by gearboxes carried by the subframe, in which event gimbal mounted nuts at each extremity of the transverse members form the universal mounting for the vertical stems.

According to one embodiment of the invention applied to a grading machine of the general character described in my Patent No. 2,074,081, a central gearbox mounted on the main grader frame carries a transverse stem and transverse guide members as there described, and at each end, the transverse guide members mount gearboxes for the vertical screwthreaded stems. In contra-distinction to the prior construction, however, both upper and lower ends of the vertical stems are anchored or fixed to the subframe and the gearboxes are trunnioned on the transverse guide members and have faced lugs or pro-

jections which ride slides or guideways provided for the purpose on the subframe structure such slides being parallel with the screwthreaded stems. The gearboxes for the respective stems are facsimiles but owing to the differing effective length of the transverse guide members consequent on different vertical and angular settings of the subframe, both gearboxes are gimbal mounted, the gimbal frames being trunnioned in lateral slots providing the requisite relative movement in the transverse guide members, the position of the gearboxes during movement of the blade being defined by their faced lugs or projections riding the beforementioned slide.

An appropriate construction of gearbox takes the form of a bracket or casing mounting a pair of bevel wheels one carrying a nut on the screw-threaded stems and the other carried in bearings in the gearbox and connected to a flexible shaft for actuation. Each gearbox is trunnioned in a gimbal frame which is in turn trunnioned at the end of the transverse guides, the arrangements of the trunnions and gimbals being such as universally to mount the gearboxes through which pass the vertical stems and which have outward projections with flat faces engaging the guideways provided for the purpose in the structure and running parallel with the stems.

The invention will be further described with reference to the accompanying explanatory drawings which illustrate by way of example one embodiment of blade grader and wherein:

Fig. 1 is a side elevation showing the longitudinal disposition of the control subframe mounting the plough circle, mouldboard and blade, and Figs. 2 and 3 are respectively a rear view and a front view of the blade mounting with the parts in their neutral or mid position.

Fig. 4 is a detail view of one of the trunnioned gearboxes to a larger scale and Fig. 5 is a longitudinal section of the central gearbox also to a larger scale.

Referring now to the drawings but first more particularly to Figs. 1-3, as in the grader described in the aforementioned Patent No. 2,074,081 a rigid front axle 1 is pivoted near the base of a central steering column 2, rotation of which for steering the grader to follow its tractor takes place about a king pin or vertical bearing 3. The column 2 depends from a U-shaped bearer 4 itself pivotal in a vertical plane about a transverse pin 5 borne in an inverted U-shaped bracket 6 which is welded to the bottom of the king pin or vertical bearing 3 and upon which bracket rests a rubbing plate 7 welded to the underside of the front end of the main frame constituted by longitudinal channel section girders 8.

The flexible mounting of the forecarriage relieves the grader frame of bending moment when traversing uneven surfaces, it being understood that the front axle 1 is itself pivoted for limited angular vertical movement in relation to the steering column 2 about a cotter or pivot 9 whereby the front wheels readily accommodate themselves to transverse surface inequalities without subjecting the main frame of the grader to torsion.

Also, as in my previous grader, a triangular drawbar assembly is provided for connecting the grader with its tractor or other towing vehicle, a draw stirrup or eye 10 being pivoted at the front end of a drawrod 11 which is carried at the front apex of the triangular drawframe con-

stituted by upper and lower girders 13 and 14 to which the drawrod 11 transmits the tractive effort through a draft cushioning spring 12.

Mechanism is provided for steering the front 5 wheels 15 from the platform 65 of the grader independently of the tractor as in my previous grader, whereby the operator may accurately steer the grader on the desired course in the wake of its tractor.

To this end the lower girder 14 of the drawbar assembly has a collar 18 at its rear end encircling a journal or bearing 19 projecting at the foot of the steering column 2 and the upper arm 13 is furnished with a pair of eyes 20 which take 10 lateral pins 21 on a double collar 22 encircling a second king pin 16 above and below a second collar 23 also encircling the king pin and which has a rearward projection mounting laterally projecting pins 24 similar to the pins 21 and constituting a horizontal bearing for a knuckle 25 through which draft stresses are transmitted to the plough circle generally designated 26 by draft arms 27 of an A frame.

When the steering mechanism is operated 25 from the platform 65, the linkrods 17 cause the drawbar to be offset from its normal position perpendicular to the front axle 1, this movement being permitted by the collars 18 and 22 turning about the king pin 16 and aligned bearing 19 respectively.

The plough circle 26 with mouldboard 28 and blade 29 is slung from horizontal bearings 30 and 31 carried by an annulus or ring 32 encircling a subframe or rectangular control structure generally designated 33 and itself adjustable vertically and laterally in relation to the main frame 8 of the grader by the means now to be described.

Approximately midway of the main longitudinal frame 8 is an inclined seat 34 for a central 40 gearbox 35 through which passes horizontally a lateral screwthreaded stem 36 anchored at its ends to arms or webs 64 bridging transverse guide members 37 and 38 disposed respectively in front of and behind the gearbox 35 and slidable laterally in relation to the seat 34 as the gearbox 35 is operated from the platform 65 of the grader to move the screwthreaded stem 36 to one side or another.

The transverse guide members 37, 38 mount 45 near their extremities secondary gearboxes 39 and 40 through each of which passes an approximately vertical screwthreaded stem, 41 for the gearbox 39 and 42 for the gearbox 40, the ends of the stems 41 and 42 being anchored or fixed to the subframe or control structure 33. It will 50 be noted by reference more particularly to Fig. 1 that the structure 33 and annular ring 32 in the neutral or mid position of the parts are inclined from the vertical, being perpendicular to the line constituting the axis of the virtual cone which has the ring 32 as its base and the draft pins 24 at its apex, the knuckle 25 being coincident with this axis which, as will be understood, shifts about its apex as the sub or control frame 55 33 is moved to adjust the depth of cut of the blade 29 and laterally as the subframe is side-shifted. Consequently for lateral movement of the subframe 33 and annulus 32 forming the base of the cone to effect sideshift of the blade 29, provision requires to be made for the central gearbox 35 to pivot about its seat 34 while bodily movement is prevented by the cap piece 43 and straps 44 which are bolted to the main frame members 8.

To this end the gearbox 35, as shown in Fig. 5,

is rotatably carried by cylindrical spigots 143, 134, the former projecting downwardly from the cap piece 43 into the top of the gearbox and the latter upwardly from the seat 34 into the bottom wall of the gearbox with their axes coincident and perpendicular to the seat 34 and in the plane of the cone base when the parts are in the neutral or mid position.

The gearbox 35 is operated from the platform 65 by a handwheel 45 through the medium of telescopic shafting 46 and the gearboxes 39 and 40 are similarly operated from the platform by large handwheels 47 and 48. The gearboxes may include a bevel drive from the telescopic shafting to the nut member encircling the screw-threaded stem, 36 in the case of the gearbox 35, 41 in the case of the gearbox 39 and 42 in the case of the gearbox 40, although in the illustrated embodiment the central gearbox 35 includes a pair of helical gearwheels 149, 136, as shown in Fig. 5, the upper wheel 149 being mounted on a short shaft 49 coupled to the telescopic shafting 46 and the lower wheel 136 being threaded on the stem 36 and being borne in the gearbox 35 between thrust races 135. On the handwheel 45 being rotated in one or other direction the second helical gearwheel or nut member 136 is correspondingly rotated and being held against lateral movement by its thrust races moves the screw-threaded stem 36 to one side or the other, in turn carrying the transverse guide members 37 and 38, the subframe 33, ring 32, and plough circle 26 to sideshift the blade 29.

To adjust the vertical position of the blade 29 the handwheels 47 and 48 are rotated to operate the gearboxes 39 and 40 and move their respective stems 41 and 42, while as aforementioned limited angular adjustment or cambering of the blade in the vertical direction can be effected through the medium of these gearboxes by setting one stem 41 in a different position to the other stem 42. To enable this to be effected the gearboxes 39 and 40 are not fixedly positioned at the extremities of the transverse guide members 37 and 38 but ride elongated slots 50 and 51 therein.

The gearbox 40 is illustrated in detail in Fig. 4 by reference to which it will be noted that a fabricated casing 52 has an upstanding bracket bearing 53 for an actuating bevel wheel 54 connected by the telescopic shafting aforementioned to the large handwheel 47, this actuating bevel being enmeshed with bevel teeth 55 formed at the upper extremity of a nut member 56 riding the screwed stem 42 and borne between thrust races 57 and 58 in the fabricated casing 52.

Projecting from each side wall of the casing 52 is a spigot or journal 59 riding in bearings provided for the purpose in a gimbal frame 60, which in turn has spigots or journals 61 projecting forwardly and rearwardly into the elongated bearing slots 50 furnished as aforementioned near the extremities of the front and rear lateral guide members 37 and 38, the arrangement being such that the gearbox 40 may rock—to the extent necessary to accommodate the angular setting of the subframe 33 for cambering the blade 29—about the journals 61 of its gimbal frame, and also to a limited extent in the longitudinal plane—to allow for the variation in the inclination of the subframe 33 as the height of the blade 29 is adjusted—on the casing journals 59 in the gimbal frame 60.

Moreover the outside wall of the gimbal frame 60 is formed with a flat rubbing face 62 riding a

vertical guide 63 which is formed for the purpose on the subframe 33 and which guide is parallel to the axis of the screwthreaded stem 42, and irrespective of the adjusted position of the subframe 33 the guide face 62 of the gearbox gimbal frame 60 maintains contact with its guide 63 thereby stabilising the mounting of such subframe in any adjusted position and relieving the stems 41, 42 of bending moment.

10 It will be understood that when the handwheels 47 and 48 are adjusted so that the screw-stems 41 and 42 are symmetrically positioned in relation to the transverse guides 37 and 38 such as would normally be the case when the blade 29 is horizontal or is otherwise positioned by movement of the annular ring 32, the spigots 61 of both gearboxes 39 and 40 occupy the inner ends of their respective pairs of slots 50 in the transverse guide members 37 and 38 so that the subframe 33 and with it the plough circle 26 and blade 29 are rigidly positioned in relation to the transverse guide members.

15 On the other hand, when the blade is cambered by adjusting the hand-wheels 47 and 48 to set the screw stems 41 and 42 asymmetrically thus to give the subframe 33 an angular setting, the pair of spigots 61 of either the gearbox 39 or the gearbox 40 will move outwardly along their respective slots 50 and under these circumstances the subframe 33 and with it the plough circle 26 and blade 29 is afforded limited lateral movement in relation to the transverse guide members 37 and 38. Immediately the machine is put to work the blade reaction stabilises the mounting and removes any likelihood of chatter or apparent instability by urging the spigots 61 at one side of the subframe to the inner ends of their positioning slots 50. The particular side at which this abutment takes place is not dependent upon 20 whether the blade is so cambered that the right or left hand end is lifted, but upon the angle of the blade to the direction of travel as adjusted by the plough circle 26, that is to say, whether the right hand end of the blade 29 is leading and the left hand end trailing or vice versa. Irrespective of which end of the blade 29 is lifted, the blade reaction when cutting and/or delivering soil causes the spigots 61 on the side of the machine containing the trailing edge of the blade to move to the inner ends of their slots and to remain there while the machine is at work with the blade so adjusted. Thus, if the plough circle is set with the right hand end of the blade 29 leading and the left hand end trailing, the spigots 61 of the left hand gearbox 39 will be urged to the inner ends of their locating slots 50 in the transverse guides 37 and 38 by the abutment between the left hand guide 63 on the subframe 33 and co-operating guide face 62 of the gearbox gimbal frame 60, whereby the thrust is directly transmitted from the subframe to the transverse guide members and the stems 41 and 42 are relieved of bending moment.

25 30 35 40 45 50 55 60 65 70 75 By reference to Figs. 1 and 3 it will be noted that the front lateral guide member 37 is further supported by rollers 70 carried on arms 71 and 72 projecting outwardly from the longitudinal girders 7 and 8 constituting the main frame thus further to stabilize the mounting of the subframe 33.

The range of angular setting or cambering of the blade afforded by the screwed stems 41 and 42 is about 25° to each side of the horizontal and additionally the blade 29 may be moved to a position for backsloping or battering in which it

may be inclined to an extent approaching 80° on each side of the horizontal by relative movement of the ring 32 carrying the plough circle 26 about the subframe 33.

To this end the ring 32 is borne on rollers 74, 75, 76, 77, carried adjacent the four corners of the rectangular subframe 33 and is furnished around its upper perimeter with internal teeth 78 with which enmeshes a pinion 79 carried in a gearbox 80 on the upper cross member 81 of the subframe 33 and mechanically connected by telescopic shafting 82 to a handwheel 83, so that the operator on the platform 65 by rotating the handwheel 83 and thus the pinion 79 effects bodily rotation of the ring 32 riding on the rollers 74—77 and takes with it the plough circle 26, mouldboard 28 and blade 29.

At the lower end of the subframe 33 a locking pin 84 is provided and co-operates with holes 85 in the annular ring 32 to fix the adjusted position of the latter, a pedal 86 being provided on the platform 65 to release the pin 84 while the position of the ring 32 is being adjusted.

The subframe 33 is a built-up structure fabricated from sheet metal and channel section frame members providing the vertical guides 63 and upper transom 81 carrying the gearbox 80 and lower transom carrying the locking pin 84, these parts being bolted and/or welded together and carrying adjustable bearings for the rollers 74—77 upon which the ring 32 rides. The projecting corners of the subframe 33 locate such ring.

As in my prior construction all movements of the blade 29 originate from the common centre, i. e., the centre of the ring 32 and subframe 33 which in the neutral position of the parts coincides with the middle of the lateral stem 36 passing through the central gearbox 35 on the longitudinal main frame of the grader and it is thus impossible for any two movements to conflict or jam.

Moreover, all movements of the blade are independently controllable from the platform without interaction, there being no loss of cut on sideshift or vice versa.

The common centre is itself movable in a rectangle limited only by the range of adjustment afforded by the lateral stem 36 and the vertical stems 41 and 42, and in addition to this bodily movement of the common centre or rotational movement of the blade 29 and associated parts, e. g., for backsloping from a set position up to 80° at one side of the machine to a similar position at the other can be had through the medium of the handwheel 83 and ring 32, while final adjustments in the set or camber of the blade and depth of cut can be accurately made on the vertical stems 41 and 42.

The plough circle 26 is equipped with conventional means enabling the blade incidence to be varied at will and the embodiment illustrated shows both front and rear axles furnished with leaning wheel mechanism, the rear axle 87 being also furnished with traversing means in the form of a nut 88 riding a screwed stem 89 operated by a handle 90 to enable the rear axle to be laterally shifted in relation to the main frame and platform of the grader, although as will be understood the means by which these ancillary movements are effected form no part of the present invention and indeed, where a simplified and cheapened machine is desired, may be omitted.

When moving the blade 29 to any required position only light pressure is necessary on the handwheels and to assist in the bodily upward

movement of the control subframe 33 carrying the ring 32, plough circle 26, mouldboard 28 and blade 29 by means of the large handwheels 41, 42 operating the screwthreaded stems 41, 42 through the gearboxes 39, 40, a pair of compression springs 66 working on guide rods 67 against an abutment 68 in the form of a webbed plate welded to and upstanding from the upper surface of the main frame 8 are connected over 10 jockey pulleys 69 by a flexible wire 73 to points on the lower part of the control subframe 33 adjacent the spaced hangers 30, 31 so as to exert an upward pull on the latter to counteract the weight of the plough circle and its associated parts. The springs 66 also function to stabilise the machine when in use.

By the present invention an improved construction of blade grading machine, patrol or maintainer is obtained, which is cheaply manufactured, more readily operated and durable in use.

What I claim is:

1. A blade mounting for a grader and like vehicles having a longitudinally extending main frame, comprising a control subframe, means for moving said subframe vertically relative to said main frame including nut members borne by said main frame and screw stems fixedly positioned in said subframe and threaded through said nut members and guides on said subframe parallel to said stems and engaging cooperating faces associated with said nut members.

2. A blade mounting according to claim 1 including a forecarriage wherein draft arms connect the lower part of the subframe with the forecarriage of the grader and the nuts are borne by lateral trunnions so as to be self-aligning with the stems and so that their faces ride the guides on the subframe as the longitudinal inclination of the latter changes consequent on vertical adjustment.

3. A blade mounting for a grader and like vehicles having a longitudinally extending main frame, comprising a control subframe carrying said blade, transverse guide members carried by the main frame means for moving said subframe vertically relative to said main frame including nuts longitudinally trunnioned adjacent the extremities of said guide members and stems fixedly positioned in said subframe and threaded through said nuts, the trunnions being laterally movable in relation to the guide members to permit lateral inclination of the subframe in relation to the main frame to camber the blade and members on said frame having guides parallel to the stems and bearing on co-operating faces associated with the nuts.

4. A blade mounting according to claim 3 including a forecarriage wherein draft arms connect the lower part of the subframe with the forecarriage of the grader and the nuts are borne by lateral trunnions in gimbal frames carrying the longitudinal trunnions so as to be self-aligning with the stems and so that faces provided for the purpose on the gimbal frames ride the guides on the subframe as the longitudinal inclination of the latter changes consequent on vertical adjustment.

5. A blade mounting according to claim 3 wherein the transverse guide members are slideable laterally in relation to the main frame and have an associated nut and transverse stem for effecting lateral adjustment between the subframe and the main frame to sideshift the blade.

6. A blade mounting according to claim 3 in-

cluding a forecarriage and draft arms, wherein a knuckle pin associated with the forecarriage pivotally mounts the draft arms to permit cambering of the blade, the knuckle pin being itself articulated to the forecarriage to permit vertical and lateral movement of the subframe and blade.

7. A blade mounting according to claim 3 including transverse guide members wherein these are supported by rollers carried on arms projecting outwardly from the longitudinal main frame thus to stabilise the blade mounting.

8. A blade mounting according to claim 3 wherein the subframe carries rollers upon which rides an annular ring of angle or channel section in turn having brackets supporting the blade or the plough circle thereof.

9. A blade mounting according to claim 3 including a forecarriage and draft arms pivotally mounted on a knuckle pin articulated to the forecarriage wherein the subframe carries rollers upon which rides an annular ring in turn having brackets supporting the blade and wherein the knuckle is substantially coaxial with the ring,

means being furnished to rotate the ring about the subframe to move the blade.

10. A blade mounting according to claim 3 wherein the subframe is a built-up structure fabricated from sheet metal and rolled section frame members secured together and wherein the sheet metal corner portions project beyond the rollers longitudinally to locate a blade-carrying ring or annulus.

11. A blade mounting according to claim 3 wherein the control subframe is quasi-rectangular and its side walls or frame members constitute the guides parallel to the stems.

12. A blade mounting according to claim 3 including a spring means exerting an upward pull on the subframe to counteract the weight of the parts and wherein such spring means operates through flexible wires anchored at widely spaced locations adjacent the foot of the subframe.

13. A blade mounting for graders according to claim 3 wherein the nuts are furnished with actuating gearing carried by gearboxes between thrust races in which the nuts rotate.

JOHN STEPHEN BURNS.
